The ornamental design for a gaming surface, as shown and described.

DESCRIPTION

A portion of the disclosure of this patent document contains material which is subject to copyright protection. The copyright owner has no objection to the facsimile reproduction by anyone of the patent document or patent disclosure, as it appears in the Patent and Trademark Office patent file or records, but otherwise reserves all copyright rights whatsoever.

FIG. 1 illustrates a gaming surface in plan view.

FIG. 2 illustrates in greater detail a central portion of the gaming surface of FIG. 1; and,

FIG. 3 illustrates in perspective a table with the gaming surface of FIG. 1.

The dash-dot-dot-broken lines represent the boundaries of the claimed design. The evenly spaced broken line showing of a table is included for the purpose of illustrating portions of an “article” and forms no part of the claimed design.
